PANEL FOR OUTDOOR ADVERTISING STRUCTURES

Filed July 3, 1929

INVENTOR
G. D. Overholtz
By W. G. Doolittle
Attorney.

UNITED STATES PATENT OFFICE

GEORGE D. OVERHOLTZ, OF LEETSDALE, PENNSYLVANIA, ASSIGNOR TO RITER-CONLEY MANUFACTURING COMPANY, OF PITTSBURGH, PENNSYLVANIA, A CORPORATION OF PENNSYLVANIA

PANEL FOR OUTDOOR ADVERTISING STRUCTURES

Application filed July 3, 1929. Serial No. 375,813.

This invention relates to panels employed in out-door advertising steel structures. In structures of the character specified and in which a plurality of panels are employed for the purpose of pasting posters thereto, considerable trouble has been encountered due to the spaces between adjacent panels when the panels are assembled on a supporting framework. These spaces provide passages for wind and rain and, unless some means are provided to effect a seal between adjacent panels, the posters are torn or destroyed after they are pasted to the panels.

The prime object of the present invention is to provide a new and improved panel construction embodying means for sealing the spaces between adjacent panels.

Other objects of the present invention are, to provide a sealing means of such a character as to afford an aligning abutment for truing up the adjacent panels; to provide a strong and durable abutment of sufficient width to permit ready engagement during assembly of the structure; and to provide an efficient panel including angle members and a sheet metal element bent along the edge thereof to form the sealing means.

In the accompanying drawings, which illustrate an application of my invention:

Fig. 1 is a perspective view of a panel constructed according to my invention;

Fig. 2, a front elevational view of an outdoor advertising structure composed of a plurality of said panels; and

Fig. 3, an enlarged sectional view on the line III—III of Fig. 2, particularly showing the sealing means.

Referring to the drawings, the panel A is formed of side members 5—5a and end members 6—6, preferably in the form of angle bars mitered and secured together by welding. Said side angles are formed with a plurality of pin-receiving openings 7, adapted to register with adjacent panels for securing the same together.

Adapted to extend from one side member to the other is a sheet metal plate or element 8. This plate at its longitudinally extending edges is adapted to extend over

flanges 9 and 9a of the side members, and thence at right angles along flanges 10 and 10a thereof. The portion 11 extending along flange 10 of member 5 is bent over and around said flange, as shown in Fig. 3. The laterally extending edges of the plate 8 are bent over end members 6—6, as at 6a.

It will be noted that the flange 10a of member 5a is slightly wider than flange 10 of member 5, to assist in forming the sealing abutment 12. Accordingly, the bent portion 11a is bent outwardly substantially at right angles, as at 12, for a sufficient distance to seat the side member 5 of an adjacent panel (see Fig. 3). The remaining portion 13 of the plate is bent back upon itself arcuately as at 13, and extends along the inner face of flange 10a. The arcuate portion 13 acts as a reinforcement for the abutment seat 12, providing added strength and rigidity.

The bent portions of the plate 8 are formed with openings 14 and 15 adapted to register with the openings 7 of the side members, and receive headed pins 16 for securing adjacent panels together.

In erecting the panels, the side member 5 of one panel may be engaged with the abutment seat 12 of an adjacent panel. Openings 7, 14 and 15 are slightly greater in diameter than the pins 16. Therefore, before securing the panels finally, they may be readily aligned by tapping, until side members 5 engage the abutment seats 12. Keys 17 may be driven through suitable slots in the pins 16, to draw the panels together tightly.

The construction described affords a tight and weatherproof seal, as well as providing a means for aligning the panels.

It will be understood that various changes and modifications are contemplated, provided they fall within the scope of the following claims.

I claim:

1. A panel for outdoor advertising structures including a metallic frame composed of angle bars, a sheet metal plate having edge portions bent over said angle bars whereby they embrace opposite sides thereof, one of said portions forming a sealing abutment for

an adjacent panel, said abutment being disposed at substantially a right angle to said portions, and a substantially arcuate portion reinforcing and connecting said abutment and the remainder of the edge portion of which it is a part.

2. In an advertising structure, panel units, each unit having an angle-bar frame member and a plate, said plates extending across one flange of the angle members and having rearwardly extending portions of U-shape closely embracing opposite sides of the remaining flanges of the angle frame members, one of said U-shaped portions having an intermediate longitudinally extending abutment in substantial parallelism with but in opposite direction to the plate engaged by the companion U-shaped member and associated parts, and a fastening means engaging said remaining flanges and causing sealing engagement of said U-shaped portions.

3. A panel for outdoor advertising structures including a metallic frame having its side members formed of angle-bars, one of the flanges of one of said angle-bars being wider than the corresponding flange of the other side member, a sheet metal plate having edge portions bent over and closely embracing a flange of each angle-bar, one of the said edge portions embracing the wider flange including an integral abutment spaced for engagement by an adjacent panel unit.

4. In an advertising structure, panel units, each unit including a metallic frame having side members formed of angle-bars, one of said angle-bars having a wider flange than the corresponding flange of the other angle-bar, and a sheet metal plate; said plate having edge portions bent over and closely embracing corresponding flanges of the angle-bars, said bent portions of the plate embracing the wider flange including an abutment spaced for engagement by an adjacent panel unit, and means passed through the wider flange of one unit and a flange of an angle-bar of an adjacent unit for securing the units together.

In testimony whereof I affix my signature.
GEORGE D. OVERHOLTZ.
